UNITED STATES PATENT OFFICE

DANIEL CUSHING, OF CAMBRIDGE, MASSACHUSETTS

FURNACE BOTTOM

Application filed July 27, 1929. Serial No. 381,555.

This invention relates to furnaces especially designed for the melting of non-ferrous metals.

It is the object of the invention to provide the bottom of such a furnace with a lining of heat-resisting blocks or bricks, said bottom and lining being so designed that the blocks may be readily assembled with the furnace bottom and that they will be securely held therein.

My invention further relates to arrangements and combinations of parts which will be hereinafter described and more particularly pointed out in the appended claims.

15 A preferred form of the invention is shown in the drawings in which

Fig. 1 is a sectional side elevation of portions of a furnace including my improved bottom;

20 Fig. 2 is a plan view of the furnace bottom shown in Fig. 1;

Fig. 3 is a detail sectional elevation, taken along the line 3—3 in Fig. 2, and

25 Figs. 4 and 5 are detail sectional views showing slight modifications.

Referring to the drawings, I have shown a furnace bottom 10 hinged at 11 to brackets 12 mounted on the under side of the furnace side walls 14. The upper surface of the bottom 10 is preferably inclined downwardly toward the tapping spout of the furnace and away from the hinge 11.

The bottom 10 is provided with an upwardly extending peripheral rim 16 having an internal annular flange 17 formed thereon. The bottom 10 is also provided with a hole or opening 18 through which a clamping bolt 20 may be inserted.

35 The heat-resisting blocks or bricks 22 used with my improved furnace bottom are preferably formed of sector shape, as indicated in Fig. 2, and are provided with peripheral grooves 24 on their outer faces, in which the annular flange 17 may be received.

40 In assembling my improved furnace bottom, a layer of heat-insulating material 30 is first placed on the bottom 10 within the rim 16, this material being of such thickness that the grooves 24 in the blocks 22 will be correctly aligned with the internal flange 17.

The blocks 22 are then placed in position but the last brick to be inserted is formed in three parts 32, 33 and 34. The side portions 32 and 33 are first inserted, this being rendered possible by the absence of the middle portion 34. After the side portions are spread apart, the middle portion 34 may be placed in position, thus locking the parts 32 and 33 and the remaining blocks 22 within the flanged rim 16 of the bottom 10.

For further security and to complete the bottom, a circular brick 40 is inserted between the inner ends of the bricks 22, this brick 40 being preferably conical in section, as shown in Fig. 1, the inner ends of the bricks 22 being correspondingly beveled. The brick 40 may be secured in position by the bolt 20 in the opening 18, previously described.

55 The bricks 22 and center brick 40 are not designed to closely abut each other but are preferably somewhat spaced apart, as indicated in Fig. 2, the spaces between the bricks being thereafter filled with sand or cement, as indicated at 44 in Fig. 1.

60 When the bottom is swung to its operative or raised position, as indicated in Fig. 1, and is suitably secured in such position, a sealing ring 46 of sand or suitable cement is placed between the bricks 22 and the side walls 14, thus effectively sealing the bottom of the 65 furnace.

65 A furnace bottom of this construction has been found particularly satisfactory for the melting of non-ferrous metals. When the bricks become badly burned or worn, they may be readily removed and replaced by loosening the single bolt 20.

70 In Fig. 4, I have shown a slight modification in which the brick 46 is provided with a shoulder 47 positioned under the flange 17. 75 This construction avoids some of the stresses caused by expansion or contraction of the rim 16.

75 Another manner of accomplishing the same result is indicated in Fig. 5 in which the rim 50 is undercut on its inner face and in which the outer face of the brick 52 is similarly bevelled to prevent upward displacement thereof.

80 Having thus described my invention and

the advantages thereof, I do not wish to be limited to the details herein disclosed, otherwise than as set forth in the claims, but what I claim is:—

5. 1. In a furnace, a bottom having an up-standing circumferential rim portion, and a plurality of heat-resisting sector-shaped lining blocks fitting snugly within said rim portion, one of said blocks being formed of 10 two substantially sector-shaped outer parts and a middle part of uniform thickness.
2. In a furnace, a bottom having an up-standing circumferential rim portion, and a plurality of heat-resisting lining blocks fitting snugly within said rim portion, said blocks being sector-shaped and one block being formed in a plurality of pieces, one of which pieces is of uniform width throughout its length.
20. 3. In a furnace, a bottom having an up-standing circumferential rim portion, a plurality of heat-resisting sector-shaped lining blocks fitting snugly within said rim portion, a center locking block, and means to secure 25 said center block in position to lock said sector-shaped blocks in said bottom.
4. In a furnace, a bottom having an up-standing circular rim portion with an internal annular flange formed thereon, a plurality of heat-resisting lining blocks cut away 30 in their outer faces to receive said flange, a center locking block, and means to secure said center block in position to prevent disengagement of said lining blocks from said 35 annular flange.
5. In a furnace, a bottom having an up-standing circular rim portion with an internal annular flange formed thereon, a plurality of heat-resisting lining blocks cut away 40 in their outer faces to receive said flange, a center locking block, and means to secure said center block in position, said block being conical in cross section with its small end downward when said bottom is in operative 45 position.
6. In a furnace, a bottom having an up-standing circumferential rim portion, a layer of heat-insulating material disposed within said rim portion, a plurality of heat-resisting 50 sector-shaped blocks resting on said heat-resisting material and a center locking block effective to prevent inward displacement of said sector-shaped blocks.
7. In a furnace, a bottom having an up-standing circumferential rim portion and a plurality of heat-resisting lining blocks fitting snugly within said rim portion, said blocks being sector-shaped and interlocking 55 with said rim against relative upward movement therein, and one of said blocks being formed in a plurality of pieces to facilitate interlocking insertion thereof after all of the one-piece sector-shaped blocks have been assembled in said bottom and within said interlocking rim.

8. In a furnace, a bottom having an up-standing circumferential rim portion with an internal annular flange, a plurality of heat-resisting sector-shaped lining blocks fitting snugly within said rim portion and grooved to receive said annular flange, means to prevent lateral displacement of said sector-shaped blocks in said bottom, and means to lock said blocks to said bottom.

9. As an article of manufacture, a heat-resisting lining block for a furnace bottom which is sector shaped in horizontal section and is provided with an outer segmental face having a circumferential groove therein and substantially spaced from the top and bottom surfaces of said block, the inner face of said block being conically and concavely segmental and said block increasing in radial length toward the bottom of said block.

In testimony whereof I have hereunto affixed my signature.

DANIEL CUSHING.
